CARTON AND BLANK FOR FORMING THE SAME

Henry Kondolf, New York, N. Y., assignor to
 Southern Kraft Corporation, New York, N. Y.,
 a corporation of Delaware

Application October 6, 1932, Serial No. 636,481
 Renewed October 16, 1936

14 Claims. (Cl. 229—27)

My invention relates to cartons for packaging, shipping, storing and vending articles of various kinds, such, for example, as chinaware dishes and cups, bottles and the like.

5 In general, my invention has for an object the provision of a carton adapted to contain a number of dishes, plates, bottles or other articles in a single unit adapted for sale as such to the consumer, and by means of which the amount of 10 loose packing, such as excelsior or the like, required for the packing of fragile articles of the class described, may be materially reduced or eliminated.

An object of my invention is to provide a 15 carton formed from a single continuous sheet of material, adapted to contain a plurality of articles for shipment, storage or sale as a single unit, and having self-formed partitions adapted to separate said articles, which partitions divide 20 the carton into a plurality of recesses each adapted to receive and retain one of said articles and shaped in accordance therewith.

A further object of my invention is to provide a 25 carton for the purpose set forth above which is provided with exterior walls of double thickness over a sufficient portion of the carton to provide mechanical strength sufficient to prevent damage or injury to the carton and its contents under 30 conditions of shipment, handling and storage.

30 A further object of my invention is to provide a blank for forming a carton of the character and for the purpose hereinabove set forth, which is of relatively simple shape or outline and is adapted to be cut from a single continuous sheet of material with a minimum of waste.

My invention has for further object such additional advantages and improvements in construction and detail as may hereinafter be found to obtain.

40 In the drawings accompanying and forming a part of this specification I have illustrated various forms in which my invention may be embodied. In these drawings,

45 Fig. 1 is a plan view of a blank for forming a carton in accordance with my invention;

Fig. 2 is a perspective view of a carton formed from the blank illustrated in Fig. 1, said carton being shown in a partly closed condition;

50 Fig. 3 is a perspective view of the carton shown in Fig. 2, in a completely closed condition;

Fig. 4 is a plan view of a modified blank;

55 Fig. 5 is a perspective view of a carton formed from the blank shown in Fig. 4, said carton being shown in a partly closed condition; and

Fig. 6 is a perspective view of the carton shown in Fig. 5, in a completely closed condition.

Similar reference numerals designate the same or similar parts in the several views of the drawings.

Referring now to the drawings and more particularly Figs. 1, 2 and 3 thereof, it will be seen that I provide a blank having a central panel 1 which is adapted to constitute the base or bottom of the carton when formed. The central panel 10 is of rectangular shape and is defined by score lines 2, 3, 4 and 5.

Adjoining the panel 1 along the score lines 2 and 4 I provide side panels 6 and 7 respectively. The sides of the panel 6 which are at right angles 15 to the score line 2 are defined by score lines 8 and 9 which are substantially in alignment with and form extensions of the score lines 3 and 5 respectively. Adjoining the side panel 6 along the score lines 8 and 9 I provide side extension 20 panels 10 and 11 respectively which are in turn adjoined along score lines 12 and 13 to end flaps 14 and 15 respectively. The end flaps 14 and 15 are provided with notches 16 and 17 adapted for mutual engagement and interlocking when the 25 blank is bent to form a carton as shown in Figs. 2 and 3.

The sides of the panel 7 at right angles to the score line 4 are defined by score lines 20 and 21 which are substantially in alignment with and 30 form extensions to the score lines 3 and 5 respectively. Adjoining the side panel 7 along score lines 20 and 21 I provide relatively narrow spacing panels 22 and 23 which are in turn adjoined along score lines 24 and 25 by partitioning 35 panels 26 and 27. The panels 26 and 27 are in turn adjoined along score lines 28 and 29 by spacing panels 30 and 31, similar to the panels 22 and 23, respectively.

Adjoining the central panel 1 along the score lines 3 and 5, I provide exterior side panels 32 and 33, respectively, which are in turn adjoined along score lines 34 and 35 by cover flaps 36 and 37 having notches 38 and 39, respectively, which 45 are adapted to mutually engage and interlock when the blank is bent to form a carton as shown in Fig. 3.

Extending outwardly from the four corners of the central panel 1, I provide straight cuts 40 50 and 41 which are in alignment with and form extensions of the score line 2, and also cuts 42 and 43 which form extensions of the score line 4. The cut 40 and 42 separate the panel 32 from the panels 10 and 26 respectively, while the cuts 41 55

and 43 separate the panel 33 from the panels 11 and 27 respectively.

In this instance, in which the partitions formed by the panels 26 and 27 are intended to traverse the carton in planes parallel to the sides 32 and 33 when the latter have been bent at right angles to the central panel 1, the following relationship should exist between various dimensions of the several panels:

- 10 The dimension *a* of the panels 32 and 33 should equal the dimension *b* of the panels 6 and 7 and the panels adjoining the latter along the score lines 8, 9, 20 and 21. The dimension *c* of panels 26 and 27 as well as the dimension *d* of panels 10 and 11 should equal the dimension *e* of the central panel 1. The dimension *f* of the spacing panels 22, 23, 30 and 31 should be equal to about one-third of the dimension *g* of the central panel 1.
- 20 It should be borne in mind, however, that in planning these dimensions and in cutting and scoring the blank, allowance must be made for the thickness of the material from which the blank is formed. Thus in practice, especially 25 when material of considerable thickness is employed, as will be evident from inspection of Fig. 2, the actual dimension *c* of the panels 26 and 27 will be slightly smaller than the dimension *d* of panels 10 and 11 due to the fact that the panels 26 and 27 are intended to form partition members lying within an enclosure formed in part by the panels 10 and 11.

It will further be obvious that, especially when material of considerable thickness is employed, 35 such score lines as have been stated hereinabove are substantially in alignment with each other or form extensions one of the other may actually be slightly offset at the junctions thereof in order to allow for proper folding of the panels and 40 proper formation of the enclosure. Thus Fig. 1 shows a slight offset between the score lines 3 and 20, which offset is provided in order to permit the panels 22, 26 and 30 to be folded within the enclosure formed by the panels 6, 45 10, 11, 14 and 15.

In forming the carton from the blank shown in Fig. 1, right angle bends are first made along the score lines 26, 21, 24, 25, 28 and 29 in such manner as to bring the spacing panels 22 and 23 50 against the adjacent surfaces of the panel 7, with the spacing panels 30 and 31 parallel to the panels 22 and 23 and extending outwardly therefrom. A right angle bend is then made along the score line 4, which brings the partitions 26 55 and 27, as well as the spacing panels 22, 23, 30 and 31, into the position in which they are shown in Fig. 2.

A right angle bend is then made along the score line 2, bringing the side panel 6 into engagement with the panels 30 and 31, and further bends are made along the score lines 8, 9, 12 and 13 to bring the panels 10, 11, 14 and 15 around the structure formed by the panels 7, 22, 23, 26, 27, 30 and 31. When the panels 14 and 15 have been 65 carried around the panel 7 they are mutually interlocked by means of the notches 16 and 17, the carton being at this point virtually in the condition in which it is shown in Fig. 2.

It will be noted from extension of Fig. 2 that 70 a partial enclosure has now been erected upon the central panel 1 as a base, which enclosure is divided into three compartments by means of the partitions 26 and 27 and their adjacent spacing panels, and which is open at the top for insertion of articles therein. The carton which I

have specifically illustrated in the drawings is of such proportions as to be well suited for the purpose of packaging three flat articles, such as plates or saucers and it may be observed at this point that the dimensions *b*, *e* and *f* indicated on Fig. 1 should correspond to the principal exterior dimensions of each of the articles intended to be packaged in the carton.

It is of course highly desirable that the dishes or other articles, whether wrapped or not, should fit into the compartments formed by the partitions 26 and 27 and the panels 10 and 11 with sufficient tightness to hold them securely.

In order to complete the enclosure, right angle bends are made along the score lines 3, 5, 34 15 and 35, bringing the panels 32 and 33 face to face with the panels 10 and 11 respectively, and bringing the covered flaps 36 and 37 into position across the hitherto open end of the enclosure, as is illustrated in Fig. 3. By means of the notches 20 38 and 39 the covered flaps 36 and 37 are interlocked and the enclosure of the carton is thereby made complete.

The carton thus formed needs, for most purposes at least, no additional sealing or wrapping. 25 The articles packaged within the same are securely held and separated from each other, thus reducing breakage or injury to a minimum. The latter property is also greatly enhanced by the fact that by far the greater portion of the carton is comprised of walls of more than one thickness. Thus panels 10 and 32 cooperate to provide a side wall of a thickness double that of the blank from which the carton is made.

In the blank and carton shown in Figs. 1, 2 33 and 3, the panels 26 and 27 are adapted to form partitions running lengthwise of the central or base panel 1, that is to say, parallel to the outer side panels 32 and 33 when the carton is completed. This form is especially suitable for packaging flat or thin articles, such as plates and saucers.

In Figs. 4, 5 and 6, however, I have illustrated a modified form of blank and carton formed therefrom, in which partitions are provided which run 45 transversely with respect to the central or base panel. This form is suitable for packaging articles, such as cups, jars, cans and the like, which are not flat or thin.

In this modification of my invention, the blank 50 is provided with a central panel 101 defined by score lines 102, 103, 104 and 105. Along the score lines 102 and 104 the panel 101 is adjoined by end panels 106 and 107, respectively.

The panel 106 is in part defined by score lines 55 108 and 109 forming extensions of the score lines 103 and 105, respectively.

Along the score line 108, the panel 106 is connected to a spacing panel 110 having a notch 111 60 therein and which is adjoined along a score line 112 by a partitioning panel 113. The latter is in turn adjoined along a score line 114 by a spacing panel 115. Along the opposite score line 109, the panel 106 adjoins a side extension panel 116 65 having a notch 117 therein.

Similarly but oppositely, the side panel 107, which is partly defined by score lines 118 and 119 forming extensions of the score lines 103 and 105, respectively, is adjoined along the score line 70 118 by a side extension panel 120 having a notch 121, and along the score line 119 by a spacing panel 122 having a notch 123 and terminating at a score line 124, where it is adjoined by a partitioning panel 125. The latter is in turn ad- 75

joined along a score line 126 by a spacing panel 127.

5 Adjacent to the panel 101 along the score lines 103 and 105 I provide outer side panels 132 and 133, respectively, which terminate at score lines 134 and 135 where they are met by cover flaps 136 and 137 having notches 138 and 139, respectively.

10 The carton is brought into the condition in which it is shown in Fig. 5 by making right angle bends along the score lines 114, 112, 108, 109, 102, 118, 126, 124, 119 and 104, and interlocking the notches 111 and 123 with the notches 121 and 117, respectively. A partial enclosure, 15 open at the top, is formed, having three compartments separated by the partitions formed by the panels 113 and 125. The side panels 132 and 133 and the cover flaps 136 and 137 are then brought up and over the partial enclosure formed in part by the panels 116, 106, 120 and 107, and by interlocking the notches 138 and 139, the carton is completely formed and the enclosure completed, as is shown in Fig. 6.

20 Roughly, the dimension l of the panels 132 and 133 should equal the dimension m of the panels 106 and 107; the dimension n of the panels 113 and 125 should equal the dimension o of the panel 101; the dimension p of the panels 110, 115, 122 and 127 should be equal to one-third 25 the dimension q of the panel 101; and the dimension l, n and p should correspond to the principal outer dimensions of each of the three articles or units intended to be packaged in the carton.

25 It will be obvious to those skilled in the art that my invention is capable of considerable modification in detail within the skill of the art, and is therefore not limited to the illustrative examples given hereinabove, but is to be broadly construed within the scope of the claims herein- 30 after made.

35 In the following claims, I have used the terms "side" and "end" walls in order to clearly define the invention. It will be obvious, however, to those skilled in the art that these terms are 40 interchangeable and are not to be considered in any sense as limitations.

45 I claim as my invention:

50 1. A blank for forming a carton adapted to hold a plurality of articles, which comprises a continuous sheet of material having a central panel adapted to serve as the bottom for the carton, end panels adjoining said central panel on two sides thereof and adapted to be bent at right angles thereto, one of said end panels having extensions adapted to be bent to form 55 with said end panels a partitioned enclosure extending upwardly from said central panel and open at the upper end; the other of said end panels carrying extension panels adapted to form 60 with said end panels a complete carton wall structure, and outer side panels adjoining said central panel on the other sides thereof, adapted to be bent at right angles to said central panel to reinforce sides of said partial enclosure, at least one of said side panels having an extension adapted to cover the open end of and complete 65 said enclosure.

70 2. A blank for forming a carton adapted to hold a plurality of articles such as dishes or the like, which comprises a continuous sheet of material having a central panel adapted to serve as a bottom for the carton; end panels adjoining said central panel on two sides thereof; and having extensions adapted to be bent to form 75 with said end panels a partitioned enclosure ex-

tending upwardly from said central panel and open at the upper end thereof for insertion of said articles therein; and outer side panels adjoining said central panel on the other sides thereof, adapted to be bent at right angles to said central panel to reinforce sides of said partial enclosure, at least one of said side panels having an extension adapted to cover the open end of and complete said enclosure, said outer side panels being adapted to mutually engage with each other and lock the completed enclosure.

75 3. A blank for forming a carton adapted to hold a plurality of articles such as dishes or the like, which comprises a continuous sheet of material having a central panel adapted to serve as a bottom for the carton; end panels adjoining said central panel on two sides thereof, adapted to be bent at right angles thereto, one of said end panels having extensions adapted to be bent to form spaced partitions extending lengthwise of said center panel and at right angles thereto, and the other and opposite end panel having extensions adapted to be bent to enclose said partitions to form a partitioned partial enclosure open at one end; and outer side panels adjoining said central panel on the other sides thereof, adapted to be bent at right angles to said central panel to reinforce sides of said partial enclosure, at least one of said side panels having an extension adapted to cover the open end of and complete said enclosure.

80 4. A blank for forming a carton comprising a sheet of material having a rectangular central panel having end panels adjoining the same at the relatively short side thereof, one of said end panels being provided with foldable extensions adapted to be bent to form with said central panel a partitioned partial enclosure open at the top, the other of said end panels being provided with extensions adapted to form the side walls of the carton, and outer side panels adjoining said central panel at the relatively long sides thereof to reinforce the sides of the carton and adapted to be bent to engage each other across the open end and complete said partial enclosure.

85 5. A blank for forming a carton adapted to hold a plurality of articles such as dishes or the like, which comprises a continuous sheet of material having a central panel adapted to serve as a bottom for the carton; end panels adjoining said central panel on two sides thereof, each of said end panels having an extension adapted to be bent to form a partitioning and spacing structure and an extension adapted to form a side, the partitioning extension of each end panel being adapted to engage and interlock with the side panel carried by the other end panel, thereby forming a partitioned partial enclosure open at the top; and outer side panels adjoining said central panel on the other sides thereof and adapted to be bent at right angles thereto to reinforce said enclosure, said outer side panels corresponding in length to the height of said enclosure, and having extensions adapted to mutually engage and interlock across the open end of said partial enclosure, thereby completing the same.

90 6. A blank for forming a partitioned carton comprising a central panel adapted to serve as the bottom, panels adjoining said central panel on two opposite edges thereof, panels carried by said first mentioned panels adapted to form therewith the walls of said carton, extensions 95

carried by said first mentioned panels adapted to extend across said central panel to provide a plurality of partitions, said extensions also being provided with spacing panels adapted to hold said partitions in predetermined relation to the walls of said carton.

7. A blank for forming a partitioned carton comprising a central panel adapted to serve as the bottom for said carton, panels adjoining said central panel on two opposite edges thereof, panels carried by said first mentioned panels adapted to form therewith the walls of said carton, extensions carried by said first mentioned panels adapted to extend across said central panel to provide a plurality of partitions for said carton, each of said first mentioned panels also being provided with a spacing panel to hold said partitions in predetermined relation to the walls of said carton, said spacing panels and said panels carried by the first mentioned panels being provided with interlocking means to hold said partitions and walls in operative position.

8. A blank for forming a carton comprising a sheet of material having a central panel, end panels adjoining two opposite edges of said panel, one of said end panels carrying panels forming the side walls of the carton, the other end panel carrying an extension forming a partition for said panel, and panels adjoining the other opposite edges of said central panel to form outer side walls for reinforcing said first material side walls, the difference in width between the end panel carrying said first mentioned side walls and said central panel being substantially equal to the thickness of said first material side walls whereby to provide a completed carton having panelled walls.

9. A carton comprising, in combination, a bottom, side and end walls, extensions attached to one of said end walls extending across said bottom to provide a plurality of partitions in said carton, said extensions also being provided with spacing panels adapted to hold said partitions in predetermined relation to the side walls of said carton, and panels carried by said bottom providing a reinforcement for said side walls.

10. A carton comprising, in combination, a bottom, side and end walls, each end wall being provided with a member for locking said side

and end walls together, an extension having a spacing panel formed with each of said members extending across said bottom to divide the carton into a plurality of compartments, said members and spacing panels cooperating to hold said extensions in predetermined relation to the walls of said carton.

11. A carton comprising, in combination, a bottom, side and end walls, each end wall being provided with a member for locking said side and end walls together, an extension having a spacing panel formed with each of said members extending across said bottom to divide the carton into a plurality of compartments, said members and spacing panels cooperating to hold said extensions in predetermined relation to the walls of said carton, and panels carried by said bottom providing a reinforcement for said side walls.

12. A blank for a bottle case comprising a bottom wall, side walls hinged thereto, top flaps at the ends of said side walls provided with oppositely extending locking tabs and notches, and compartment forming members hinged to said bottom and extending parallel to said side walls and provided with oppositely extending locking notches.

13. In a carton made from a unitary blank and having side and end walls, and a bottom, partition members carried by one of said end walls, said partition members having extensions contacting with the side walls of the carton to maintain said partition members in spaced relation to said side walls, said side walls comprising extensions of the other end wall, said side walls carrying extensions having interengaging means to lock said side walls in operative position.

14. In a carton made from a unitary blank and having side and end walls, and a bottom, partition members carried by one of said end walls, said partition members having extensions contacting with the side walls in spaced relation to said side walls, said side walls carrying extensions of the other end wall, said side walls carrying extensions having interengaging means to lock said side walls in operative position, said extensions having sufficient area to reinforce the end wall carrying the partition members.

HENRY KONDOLF. 50
